WELL DRILLING APPARATUS

Rodolfo Ogarrio, New York, N. Y., assignor to The
Texas Company, New York, N. Y., a corporation
of Delaware

Application February 27, 1942, Serial No. 432,570

2 Claims. (Cl. 255—4)

This invention relates to the drilling of wells and more particularly to a method and an apparatus for drilling oil by rotating a cutting tool against the formation by means of a turbine or motor disposed directly above the cutting tool and supplied with a fluid from the surface through a non-rotatable pipe string extending from a pump at the surface to the motor or turbine with the well bore. The principal object of the invention is to provide a method and an apparatus through the use of which a good mud cake will be built up on the walls of the well bore.

In the rotary method of drilling a well a cutting tool or bit secured to the lower end of a pipe string is adapted to cut or bore into the formation when the pipe string is rotated from the surface. In this method, fluid such as drilling mud is pumped downwardly through the rotating drill pipe string from which it passes outwardly through openings in the bit. The mud picks up the cuttings and carries them in suspension upwardly to the surface between the drill pipe string and the walls of the bore. The drilling mud fluid serves another important purpose and this is to deposit a layer of mud, usually termed a mud cake, on the walls of the bore. This mud cake serves to seal the formations transversely by the well bore and thus to prevent or retard water infiltration. The mud cake also tends to maintain the walls, or, in other words, to prevent crumbling and sloughing of the formations.

In another method of well drilling, a fluid, which may be a drilling mud, is pumped downwardly through a non-rotating tubing or pipe string to a motor such as a turbine disposed at the lower end of the string and attached directly to a cutting tool or drilling bit. The mud fluid being pumped downwardly under pressure through the turbine causes rotation of the drilling bit and the cuttings are picked up and carried in suspension upwardly to the surface through the space between the pipe string and the walls of the bore in a manner similar to that previously described. This method of well drilling is described in several U. S. Letters Patent, for example, the patent to Capeliuschnicoff, No. 1,681,094, granted August 14, 1928. It has been found to be very difficult, if not impossible, to build up a good mud cake on the walls of a well drilled in this manner, since the mud fluid usually passes straight upwardly through the drilled formations following the most direct path. Channelling of the formations frequently occurs and portions of the softer strata are often washed away thus leaving cavities and an irregular hole.

As stated hereinbefore, it is the principal purpose of this invention to provide a method and means through the use of which a uniform mud cake can be obtained on all of the well bore surface.

5 In accordance with the invention, means is provided on the exterior of the non-rotatable pipe string for imparting a rotary or spiral movement to the mud during its travel from the bit upwardly to the surface. By this rotary motion a certain centrifugal force is imparted to the mud and, due to this centrifugal force and also the fact that, due to the swirling movement of the mud all of the surface of the well bore will be contacted by the mud, an efficient mud cake is provided. Were it not for this rotary or spiral movement of the mud, the fluid in passing upwardly would, as has been explained, seek the most direct path and channeling of the walls of the well bore would result. Because of this channelling action, parts of the formations might be loosened so as to fall into and plug the well bore; but, what is probably more important, it would be substantially impossible to secure a mud cake of good consistency and uniform thickness on the walls of the bore.

10 In carrying out the invention I have provided on the exterior surface of the non-rotatable pipe string a fin or flange extending outwardly, substantially radially. The fin or flange is formed in the shape of a spiral or helix and therefore when the mud starts upwardly from the drilling bit a rotary or spiral motion will be imparted to the mud, and in this manner channelling will be prevented while at the same time a uniform mud cake will be built up on the walls of the bore.

15 For a better understanding of the invention reference may be had to the accompanying drawing in which the single figure discloses a vertical elevation, partly in section, of a well bore with the drilling apparatus in place.

20 Referring to the drawing, a well bore 10 is shown as having been drilled through various formations or strata by means of a cutting tool or bit 12 adapted to be rotated by means of a fluid motor or turbine 14 secured at the lower end of a pipe string 16. A mud pump 18 at the surface adapted to be driven by means of a suitable engine 20 is provided with an in-take pipe or tube 22 extending into a mud sump or pool 24. A flexible hose 26 conducts the mud fluid under pressure from the pump 18 to the upper end of the pipe string 16 and the pressure of the mud acting upon the elements, not shown, of the turbine 14 causes rotation of the shaft of the turbine

and thus the cutting tool 12 in a manner well known to those versed in the art.

The construction of the motor or turbine 14 does not form a part of this invention and therefore the interior of the turbine has not been illustrated. Any suitable device of this kind, such, for example, as that disclosed in the aforementioned patent to Capelluschnicoff, No. 1,681,094, or the patent to Verneuil, No. 1,412,430, granted April 11, 1922, may be used. It is also understood that the pipe string 16 will be suspended in the hole 10 in any suitable manner so that additional pipe sections can be added as the string moves downwardly.

Each section or length of the pipe forming the string 16 is provided around its exterior surface with a fin or flange 28, this flange being formed in the shape of a helix or spiral and being attached to the pipe in any suitable manner, as by welding. While it is not absolutely essential, it is preferred that the flange 28 be positioned on the pipe sections in such a manner that when the threaded connections between adjacent sections of pipe are made up the flange will form a substantially continuous spiral.

In operation the mud which passes through the turbine 14 will be exhausted either directly from the lower end of the turbine or, if desired, through suitable holes in the drill bit 12 so that it will pick up the cuttings made by the bit and conduct them in suspension to the surface. Due to the provision of the spiral flange 28 the mud fluid in passing upwardly beyond the upper end of the turbine 14 will tend to follow the spiral direction of the flange, as is indicated diagrammatically by the dotted line 30. A swirling movement will thus be imparted to the mud and the fluid will thereby be caused to contact all of the surface of the well wall. Assuming a rate of mud fluid flow of, say, 400 gallons per minute for a well having a depth of around 4000 feet, an appreciable centrifugal force will be generated in the mud fluid which will cause an increased pressure between the mud fluid and the well walls, and the plastering action of the fluid will be considerably amplified. In this manner a mud cake 32 will be built up to adhere to and line the walls of the well bore in such a manner as to prevent crumbling of the formations and water infiltration. Channeling of the formation walls by the passage of the mud fluid will be prevented.

The width of the flange 28 may vary somewhat in accordance with the rate of mud flow, the depth of the hole, etc. It is not intended that the

flange be so wide as to contact the walls of the hole since this would render difficult the removal of the pipe string from the hole.

Although the pipe string 16 has been described as formed of a plurality of lengths of steel pipe, it is also contemplated that a flexible pipe or conduit of rubber or the like can be utilized to conduct the mud fluid to the turbine 14. Such a conduit can obviously consist of one continuous length or of a plurality of lengths suitably connected together. The spiral fin or flange can either be formed integrally with the flexible tube or can be attached to the outer surface by any suitable means as by cement.

Obviously many other modifications and variations of the invention, as hereinbefore set forth, may be made without departing from the spirit and scope thereof, but only such limitations should be imposed as are indicated in the appended claims.

I claim:

1. A well drilling apparatus comprising a cutting tool, a fluid driven motor connected to and directly above said tool for rotating said tool against the formation, a mud pump at the surface, a non-rotatable conduit extending from said pump to said motor and adapted to conduct mud fluid under pressure from said pump to said motor, the fluid exhausted from said motor passing upwardly to the surface around said conduit, and means for imparting a rotary motion to said upwardly flowing fluid comprising a spiral flange secured to and coextensive with the exterior of said conduit, the centrifugal force developed by said rotary motion causing the mud fluid to plaster uniformly the walls of the hole.

2. A well drilling apparatus comprising a cutting tool, means for rotating said tool against the formation, said means comprising a fluid driven motor connected to and directly above said tool, a mud pump at the surface, a non-rotatable conduit connecting said motor and said pump and adapted to conduct mud fluid under pressure from said pump to said motor, and means for imparting a rotary motion and centrifugal force to the fluid returning from the motor to the surface through the annular space between said conduit and the walls of the well, said means comprising a spiral fin projecting radially from the exterior surface of said conduit and extending throughout the length of the conduit.

RODOLFO OGARRIO.
